INJECTOR

Erich Henkel, Calumet City, Ill., assignor to The
Superheater Company, New York, N. Y.

Application August 20, 1932, Serial No. 629,621

13 Claims. (Cl. 103—271)

The present invention relates to injectors and has particular reference to injectors of the type in which the amount of water supplied to the injector is governed by varying the area of the opening for flow of water into the water nozzle or cone of the injector.

The invention is well suited to exhaust steam injectors of the Metcalfe type but it is to be understood that it is in no wise restricted in its application to any special type of injector.

The principal object of the invention is to improve upon constructions heretofore employed for effecting a variable water inlet opening at the water nozzle of the injector and to provide an injector having water regulating means of the above described general character in which the construction is such that leakage of water to the steam chamber of the injector, as well as leakage of steam from the steam chamber to the water passages of the injector ahead of the water nozzle, is prevented without having to resort to the use of packing elements.

Further and more detailed objects of the invention together with the advantages to be derived from its use will be more fully set forth in connection with the ensuing description of a preferred embodiment of the invention as applied to an injector of the Metcalfe type.

In the accompanying drawing forming a part of this specification:

Fig. 1 is a longitudinal central section of an exhaust steam injector embodying the present invention and

Fig. 2 is a view showing a part of the structure of Fig. 1 on a larger scale and with a movable element therein shown in part in one position and in part in a second position.

Referring now to the drawing, the injector body indicated generally at A comprises casing portions 10 and 11 which, if desired, may obviously be made integral with each other. Casing portion 10 provides a main steam chamber 12 to which exhaust steam is supplied through the inlet 13 controlled by the exhaust valve 14. Valve 14 is urged toward the closed position shown in the figure by spring 15 and is opened by pressure fluid such as live steam admitted to piston 16 through supply passage 17. The main steam nozzle 18 is removably secured in the body portion 10 as by means of the threaded and flanged joint indicated at 19. It will be evident that this nozzle may, if desired, be made integral with the casing or may be fixed thereto in any suitable manner providing a fixed connection. As will herein-after more fully appear, it is desirable in connec-

tion with the exercise of the present invention that the joint, if any, between the casing portion 10 and the nozzle 19 be fluid pressure tight.

Nozzle 18 provides communication between the main steam chamber 12 and the water nozzle or cone 20 to which water is supplied by way of inlet conduit 21 and water chamber 22. In the specific form of injector illustrated a secondary steam nozzle 23 is employed, steam being conducted from chamber 12 to chamber 24 through a passage at the side of the injector, not shown in the drawing.

In the casing portion 11 are mounted the combining tube 25 and delivery tube 26, which may be of any suitable form, the chamber 27 around the combining tube being in communication with the usual overflow outlet 28 and the delivery tube 26 being in communication through the usual check valve 29 with the delivery conduit 30.

In order to enable the injector to deliver against high pressures, a nozzle is provided to which supplementary high pressure live steam is admitted by way of chamber 32 and in order to permit the injector to operate when exhaust steam is not available, live steam at reduced pressure is admitted to chamber 12 through ports 33 which place this chamber in communication with supply chamber 34.

The injector structure just described is known and need not be described herein in further detail. It is further to be understood that the injector just described is shown for purposes of illustration only and that insofar as the present invention is concerned, the injector structure may vary considerably.

Considering now more particularly the portion of the structure embodying the present invention, there is provided around the main steam nozzle 18 an annular movable element 35 hereinafter referred to as a shroud, which operates to regulate the size of the opening through which water flows to the water nozzle 20 from chamber 22. In the embodiment illustrated, the nozzle 18 is recessed forward of the joint 19 to provide an annular space 36 in which the cylindrical portion 35a of the shroud is slidably mounted. The forward portion of nozzle 18 is preferably provided with an external cylindrical surface 18a which provides a bearing for the forward portion 35b of the shroud.

Free communication is advantageously provided between chamber 22 and space 36 between the shroud and nozzle 18 by means of one or more ports 42 in the shroud, and space 36 is also advantageously placed in communication with

space 36 by means of a suitable passage such as groove 43, which in the illustrated embodiment is in nozzle 18. Obviously chamber 22 and space 36 may be connected directly by a suitable passage in the casing.

10 Rotatably mounted in the casing portion 10 is the control member 37 having at its inner end an eccentrically disposed pin 38 projecting into a suitable slot in the shroud 35. Member 37 comprises a stem 39 passing through a suitable packing gland 40 to the exterior of the casing portion 10 and having mounted thereon the operating handle 41 for turning the member 37.

15 The operation of the above described arrangement to regulate the amount of water fed to the injector will be largely obvious from the drawing. In Fig. 1, shroud 35 is shown in fully retracted position with respect to the water nozzle 20, affording maximum opening for flow of water 20 from chamber 22 into the water nozzle. The lower half of the shroud in Fig. 2 is shown in the same position as that shown in Fig. 1, while the upper half of the shroud in this figure is shown with the member 37 turned so that the shroud is moved as far forward with respect to the nozzle 20 as possible, thus affording the minimum opening from chamber 22 into the water nozzle. It will be evident that any desired intermediate size of water inlet opening 25 may be obtained by turning the control lever 41 to move shroud 35 between the position of maximum opening shown in Fig. 1 and the position of minimum opening shown in the upper half of Fig. 2. Due to the free communication between spaces 36 and 44 and chamber 22, by way of port 42 and passage 43, rapid and easy movement of the shroud from a position such as that shown in the upper half of Fig. 2 to a position such as that shown in the lower half of the figure is not interfered with by water trapped in these spaces.

30 The use of a movable element to vary the size of the water opening at the inlet of the water nozzle of the injector is not new per se but heretofore this type of water regulation has been effected by the use of a movable steam nozzle.

35 By interposing between a fixed steam nozzle and the casing of the injector a movable shroud of the character just described, it is possible to retain the advantages of water regulation at the water nozzle, which advantages are well known and need not be enlarged upon herein, while at the same time eliminating the disadvantages due to the employment of a movable steam nozzle.

40 It is highly important that the steam nozzle be very accurately centered with respect to the water nozzle, and by employing a fixed steam nozzle, the highly desirable exact alignment of the steam and water nozzles may be maintained because of the fact that the steam nozzle is rigid and is not subject to eventual misalignment due to wear as is the case when a sliding nozzle is employed. Furthermore, the employment of the fixed nozzle precludes the possibility of leakage 45 of steam from the steam chamber 12 around the outside of the steam nozzle and into the water chamber of the injector, thus avoiding undesirable heating of the water prior to its contact with steam in the jet-forming nozzle. Likewise, the 50 fixed and pressure tight joint between the steam nozzle and the casing of the injector precludes the leakage of water from the water chamber of the injector past the nozzle to the main steam chamber of the injector. This is important in 55 the case of injectors to which water is supplied

to the injector under pressure, as for example in boiler feed water apparatus wherein water is supplied to an injector from a boiler feed pump, the injector serving to heat and further elevate the pressure of the water supplied to it. When water is supplied to chamber 22 under pressure, port 42 and passage 43, which permit free flow of water and consequent equalization of pressure between this chamber and spaces 36 and 44, are of particular advantage.

80 It will be apparent to those skilled in the art that the present invention may be applied with equal facility and advantage to many different types of injectors and that insofar as the present invention is concerned, the pressure of the steam and also the character thereof (that is, whether live steam or exhaust steam) supplied to the steam nozzle is immaterial. Also it will be evident that the provision of nozzles such as the supplementary high pressure nozzle 31 and the secondary steam nozzle 23 may be omitted without affecting the 85 present invention.

90 What I claim is:

1. In an injector, in combination, a casing providing a steam chamber and a water chamber, a steam nozzle mounted in said casing between said chambers, a water nozzle mounted in said casing on the side of the water chamber remote from the steam chamber, said steam nozzle extending through said water chamber and having a cylindrical outer surface adjacent to the water nozzle, a shroud around said steam nozzle, said shroud having a tapered outer surface adjacent to said water nozzle and a cylindrical inner surface in sliding contact with the cylindrical outer surface of said steam nozzle and means for moving said shroud axially of the steam nozzle to vary the inlet opening for water between said nozzles.

105 2. In an injector, in combination, a main steam nozzle, a water nozzle spaced from the steam nozzle, a shroud around said steam nozzle, said shroud and said main steam nozzle having axially spaced cylindrical bearing surfaces in sliding engagement for guiding the shroud, said shroud having a portion adjacent to the inlet of said water 110 nozzle for varying the inlet opening of the water nozzle upon movement of the shroud and means for moving said shroud with respect to said steam nozzle.

115 3. In an injector, in combination, a casing having spaced steam and water chambers, a steam nozzle fixed to the casing between said chambers and extending through said water chamber, a water nozzle fixed in the casing on the side of the water chamber remote from the steam chamber and a movable shroud slidably mounted at spaced places on said steam nozzle and radially spaced therefrom intermediate said spaced places whereby to provide an annular space between the steam nozzle and the shroud, said annular space being 120 located within said water chamber and means for moving said shroud to vary the area of the opening between said water chamber and said water nozzle.

125 4. In an injector, in combination, a casing having spaced steam and water chambers, a steam nozzle fixed to the casing between said chambers and extending through said water chamber, a water nozzle fixed in the casing on the side of the water chamber remote from the steam chamber and a movable shroud slidably mounted at spaced places on said steam nozzle and radially spaced therefrom intermediate said spaced places whereby to provide an annular space between the steam nozzle and the shroud, said annular space 130

- being located within said water chamber and being in substantially open communication therewith and means for moving said shroud to vary the area of the opening between said water chamber and said water nozzle. 5
5. In an injector, in combination, a casing providing a steam chamber and a water chamber, a steam nozzle mounted in said casing, a recess formed by adjacent wall portions of the steam nozzle and the casing, a water nozzle in communication with said water chamber, a shroud around said steam nozzle, said shroud comprising a portion slidably mounted in said recess and a portion adjacent said water nozzle for varying the inlet opening thereto upon movement of the shroud, said recess being in communication with said water chamber, and means mounted in said casing for moving said shroud. 10
6. In an injector, a casing, a main steam nozzle in said casing, a water nozzle in said casing, said nozzles being fixed in spaced relation to provide a water chamber therebetween in communication with the water nozzle, and means for regulating the rate of flow of water from said chamber comprising an annular member interposed between the main steam nozzle and the water nozzle and shiftable to alter the area for flow of water from said chamber to the water nozzle. 15
7. In an injector, a casing, a main steam nozzle in said casing, a water nozzle in said casing, said nozzles being fixed in spaced relation to provide a water chamber therebetween in communication with the water nozzle, and means for regulating the rate of flow of water from said chamber comprising an annular member interposed between the main steam nozzle and the water nozzle, said annular member being movably mounted in said casing and having a portion maintaining contact with the exterior of said main steam nozzle in different positions of adjustment of said annular member, and means for moving said annular member with respect to the water nozzle to alter the area for flow of water from said water chamber. 20
8. In an injector, a casing, a main steam nozzle in said casing, a water nozzle in said casing, said nozzles being fixed in spaced relation to provide a water chamber therebetween in communication with the water nozzle, and means for regulating the rate of flow of water from said chamber comprising an annular member interposed between said nozzles, said annular member being movably mounted and having a portion for guiding all of the water from said water chamber into said water nozzle in different positions of adjustment of said annular member, and means for moving said annular member toward and away from the water nozzle to alter the area for flow of water from said water chamber. 25
9. In an injector, in combination, a casing, a main steam nozzle, a water nozzle, said nozzles being fixed in said casing in spaced relation to provide a water chamber therebetween, said water chamber being in communication with said water nozzle, and means for regulating the rate of flow of water from said water chamber comprising an axially movable shroud outside of said main steam nozzle for varying the area for flow of water from said water chamber. 30
10. In an injector, in combination, a casing providing a steam chamber and a water chamber, a main steam nozzle fixed in said casing, a recess formed by adjacent wall portions of said main steam nozzle and said casing, a water nozzle fixed in said casing and in communication with said water chamber, means for regulating the rate of flow of water from said water chamber comprising a shroud around said main steam nozzle, said shroud comprising a portion slidably mounted in said recess and a portion adjacent to said water nozzle for varying the inlet opening thereto upon movement of the shroud, and means mounted in said casing for moving said shroud. 35
11. In an exhaust steam injector, a casing providing a main exhaust steam chamber, a main exhaust steam nozzle fixed in the casing and in communication with said chamber, a water nozzle fixed in the casing and spaced from the main exhaust steam nozzle to provide a water chamber, and means for regulating flow of water from said water chamber to said water nozzle comprising an annular shroud slidably mounted in the casing between said main exhaust steam nozzle and said water nozzle. 40
12. In an exhaust steam injector, a casing providing a main exhaust steam chamber, a main exhaust steam nozzle fixed in the casing and in communication with said chamber, a water nozzle fixed in the casing and spaced from the main exhaust steam nozzle to provide a water chamber, and means for regulating flow of water from said water chamber to said water nozzle comprising an annular shroud slidably mounted in the casing around said main exhaust steam nozzle and spaced therefrom to provide an annular space between the nozzle and the shroud, said main exhaust steam nozzle providing a fixed partition between said shroud and said main exhaust steam chamber for preventing flow of steam from said chamber to said annular space. 45
13. In an injector, a casing providing a water chamber and a main steam chamber, said chambers being axially spaced in the casing, a main steam nozzle fixed in said casing between said chambers and extending axially across said water chamber, the fixed connection between the main steam nozzle and the casing preventing flow of fluid between said chambers externally of the nozzle, and means for regulating the flow of water from said water chamber comprising an annular shroud slidably mounted in the casing around said main steam nozzle. 50

ERICH HENKEL.
